(57) CLAIM

The ornamental design for a table mounted phone holder, as shown and described.

DESCRIPTION

FIG. 1 is a top-rear perspective view of a table mounted phone holder showing my new design;
FIG. 2 is a perspective view thereof, shown in an environment of use with an unclaimed poker table;
FIG. 3 is a front elevational view thereof;
FIG. 4 is a top plan view thereof;
FIG. 5 is a bottom plan view thereof;
FIG. 6 is a right side elevational view thereof;
FIG. 7 is a left side elevational view thereof;
FIG. 8 is a rear elevational view thereof; and,
FIG. 9 is a top-front perspective view showing my new design.
Broken lines illustrate environmental subject matter and form no part of the claimed design.
